UNITED STATES PATENT OFFICE.

RICHARD GERVASE KIRTON, OF PERTH, WESTERN AUSTRALIA, AUSTRALIA.

METHOD OF MAKING CONCRETE STRUCTURES.

Application filed August 7, 1922. Serial No. 580,292.

To all whom it may concern:

Be it known that I, RICHARD GERVASE KIRTON, a subject of the King of England, residing at Perth, Western Australia, 5 Australia, have invented certain new and useful Improvements in Methods of Making Concrete Structures, of which the following is a specification.

This invention is for improvements in or 10 relating to concrete structures of the type wherein vertical tubular members are placed side by side along the site to be occupied by the wall and the wall is then built up around them by a succession of 15 pourings of concrete.

According to the present invention the 20 method of building concrete walls or other structures vertically in the position they are to finally occupy, is characterized by 25 rounding the tubular casing or casings which are preferably tapered towards the base with a wrapping of material such as felt lubricated to permit easy sliding of the tube. This has the double advantage of allowing the tubes to be easily withdrawn and of increasing the mass of material at the 30 base of the wall.

It has been found that if tubular members 35 are built into a wall of any reasonable height, say 6 feet high or more without any surrounding lubricated wrapping, it is impossible to withdraw them even though the members be tapered and the concrete has only just set.

In the accompanying drawings which 40 illustrate one method of carrying out this invention as applied to the construction of a hollow concrete wall whereof the cavities are utilized for ventilation purposes;

Figure 1 is a vertical transverse section 45 showing the shuttering and a tubular casing in position prior to the pouring in of the concrete;

Figure 2 is a sectional elevation through 50 the centre of the finished wall;

Figure 3 is a vertical transverse section 55 through the wall on the line 3-3 of Figure 2; and

Figure 4 is a horizontal section through 60 the wall on the line 4-4 of Figure 2.

Like numerals indicate like parts in the 65 various figures.

A foundation 1 in the form of concrete blocks is laid along the line to be occupied 70 by the wall. Placed upon the top of this

foundation is a horizontal tube 2 having in it a series of short upwardly directed branches 3 and at intervals along its length a number of side perforations 4. Erected upon the tube 2 and closely fitting 60 at the bottom the branches 3 is a series of vertical tubular casings 5 which are of circular cross-section and are constructed of thin sheet metal. These casings are, in height slightly more than that of the wall 65 which is say one story high or about 10 feet, and are tapered towards their lower end. They are surrounded with a substance such as a wrapping of greased felt to prevent the concrete from sticking to them and are provided with a lifting pin 6 at the top. Shuttering boards 7 are erected at each side leaving a clearance between the casings and the boards, and wooden blocks 8 or the like are fitted between the side openings 4 in the 70 tube 2 and the upper end of some of the tubular casings and the shuttering-boards in order to provide communication between the cavities and the external atmosphere on one or both sides of the wall. Finally, the 75 concrete 9 is poured in until the space between the casings and the shuttering-boards is completely filled in and the whole is left to set.

When the concrete is sufficiently set the 80 casings 5 are withdrawn from the top. The greased felt or other lubricated substance to prevent sticking left in the cavities may be removed if desired or may be allowed to remain. Obviously material other than felt 85 may be employed but felt is found convenient as it is ordinarily of sufficient thickness to yield to the inequalities of the casings when they are withdrawn. It will be appreciated that the casings cannot be 90 made accurately true without needless expense, and that the wrapping round them must be of such thickness as to yield sufficiently to allow for this lack of accurate construction as the casings are withdrawn. 95

Instead of greasing the felt or other substance, it may be lubricated for example by graphite as all that is required is that a lubricated surface shall be presented to the casing to obviate sticking between the casing and wrapping. The more convenient method of lubricating the wrapping, will of course be to impregnate it with the grease or other lubricant used.

It will be readily appreciated that on ac- 110

count of the casings being tapered towards the lower end the mass of the concrete is distributed more or less proportionately to the load taken by the wall, thus at the lower 5 end of the wall where the load is heaviest, there is more concrete to carry it than at the upper end where the load is less.

Any convenient arrangement may be made for connecting the tubular casings or cavities 10 in the wall with the external atmosphere, for example, some may be connected by a lateral passage at the top with the interior of a room of the building to serve as a ventilation opening for the ingress of air from 15 outside and others may be connected at the top with the external atmosphere by a lateral passage to serve as an outlet for the egress of air from the interior of the building, the air entering the cavities by way of 20 the lateral passages leading to the side openings in the tube 2. With this arrangement the respective ingress and egress casings or 25 cavities may be partitioned off in the horizontal bottom tube 2 and the various openings for the air may be controlled by flap valves.

This invention may be applied to other structures such for example as gate-posts in 30 which case the post would have embedded in it a tapered tube with its small end downwards, which tube would be withdrawn after the casting of the post so that a light but strong post would result.

The tubes may be of any desired cross- 35 section but are preferably circular, being in this form more easily withdrawn. Further, where necessary and desirable reinforcing means may be provided in the customary way outside the casings.

40 In the wall construction, instead of fitting the blocks or cores 8 between the shuttering boards and the bottom tube 2, the tube may be provided with laterally directed branches in addition to the upwardly directed ones.

45 It is known to use horizontal and vertical air-shafts in concrete walls and to have these interconnected and no claim is made in the present specification for the use of a horizontal tube embedded in a wall or other 50 structure except when it is used with the tubular casings surrounded with a greased substance or wrapping to prevent adhesion of the concrete to the casings.

I claim:—

55 1. The method of constructing vertically in the position it is to finally occupy a hollow concrete structure consisting in wrapping a tube with compressible material lubricated to permit easy sliding of the tube 60 out of said wrapping, which tube is of the length and size necessary for a core for the hollow portion of the structure, mounting said tube vertically in the site where the structure is to be formed, placing the concrete round the tube and after allowing the same to set withdrawing 65 the tube from its wrapping.

same to set withdrawing the tube from its wrapping.

2. The method of constructing vertically in the position it is to finally occupy a hollow concrete structure consisting in wrapping a tube with felt lubricated to permit easy sliding of the tube out of said wrapping, which tube is of the length and size necessary for a core for the hollow portion of the structure, mounting said tube vertically in the site where the structure is to be formed, placing the concrete round the tube and after allowing the same to set withdrawing the tube from its wrapping. 70

3. The method of constructing vertically in the position it is to finally occupy a hollow concrete structure consisting in wrapping a tapered tube with material lubricated to permit easy sliding of the tube out of 75 said wrapping, which tube is of the length and size necessary for a core for the hollow portion of the structure, mounting said tube vertically in the site where the structure is to be formed with the small end downwards, placing the concrete round the tube and after allowing the same to set withdrawing the tube from its wrapping. 80

4. The method of constructing vertically in the position it is to finally occupy a hollow concrete structure consisting in wrapping a tapered tube with compressible material lubricated to permit easy sliding of the tube out of 85 said wrapping, which tube is of the length and size necessary for a core for the hollow portion of the structure, mounting said tube vertically in the site where the structure is to be formed with the small end downwards, placing the concrete round the tube and after allowing the same to set withdrawing the tube from its wrapping. 90

5. The method of constructing vertically in the position it is to finally occupy a hollow concrete structure consisting in wrapping a tapered tube with felt lubricated to permit easy sliding of the tube out of 95 said wrapping, which tube is of the length and size necessary for a core for the hollow portion of the structure, mounting said tube vertically in the site where the structure is to be formed with the small end downwards, placing the concrete round the tube and after allowing the same to set withdrawing the tube from its wrapping. 100

105 6. The method of constructing vertically in the position it is to finally occupy a concrete wall having a plurality of vertical conduits formed therein, consisting in wrapping a plurality of tubes each with compressible material lubricated to permit easy 110 sliding of the tubes out of said wrappings, which tubes are of the length and size necessary for cores for the conduits to be formed in the wall, mounting said tubes vertically spaced along the site to be occupied by the wall, placing the concrete 115

round the tubes and after allowing the same to set withdrawing the tubes upwards from their wrappings.

7. The method of constructing vertically in the position it is to finally occupy a concrete wall having a plurality of vertical conduits formed therein, consisting in wrapping a plurality of tubes each with felt lubricated to permit easy sliding of the tubes out of said wrappings, which tubes are of the length and size necessary for cores for the conduits to be formed in the wall, mounting said tubes vertically spaced along the site to be occupied by the wall, placing the concrete round the tubes and after allowing the same to set withdrawing the tubes upwards from their wrappings.

8. The method of constructing vertically in the position it is to finally occupy a concrete wall having a plurality of vertical tapered conduits formed therein, consisting in wrapping a plurality of tapered tubes each with material lubricated to permit easy sliding of the tubes out of said wrappings, which tubes are of the length and size necessary for cores for the conduits to be formed in the wall, mounting said tubes vertically spaced along the site to be occupied by the wall, placing the concrete round the tubes and after allowing the same to set withdrawing the tubes upwards from their wrappings.

30 9. The method of constructing vertically in the position it is to finally occupy a concrete wall having a plurality of vertical

tapered conduits formed therein, consisting in wrapping a plurality of tapered tubes each with compressible material lubricated to permit easy sliding of the tubes out of said wrappings, which tubes are of the length and size necessary for cores for the conduits to be formed in the wall, mounting said tubes vertically spaced along the site to be occupied by the wall, placing the concrete round the tubes and after allowing the same to set withdrawing the tubes upwards from their wrappings.

10. The method of constructing vertically in the position it is to finally occupy a concrete wall having a plurality of vertical tapered conduits formed therein, consisting in wrapping a plurality of tapered tubes each with felt lubricated to permit easy sliding of the tubes out of said wrappings, which tubes are of the length and size necessary for cores for the conduits to be formed in the wall, mounting said tubes vertically spaced along the site to be occupied by the wall, placing the concrete round the tubes and after allowing the same to set withdrawing the tubes upwards from their wrappings.

In testimony whereof I have signed my name to this specification in the presence of two subscribing witnesses.

RICHARD GERVASE KIRTON.
